UNITED STATES PATENT OFFICE.

ALEXANDER P. CRARY, OF NEW YORK, N. Y.

MOLD-FORM FOR CONCRETE WALL CONSTRUCTION.

1,044,862.

Specification of Letters Patent.

Patented Nov. 19, 1912.

Application filed October 9, 1909. Serial No. 521,921.

To all whom it may concern:

Be it known that I, ALEXANDER P. CRARY, a citizen of the United States, residing at the borough of Manhattan, city of New York, in the county of New York and State of New York, have invented a certain new and useful Improvement in Mold-Forms for Concrete Wall Construction, of which the following is a specification, reference being 10 had therein to the accompanying drawings, forming part thereof.

My invention relates to mold forms for concrete wall construction, particularly in high, massive concrete work where the wall 15 is thick or where only one face thereof is exposed, as in dams, canals, locks, piers, bulkheads, retaining walls, and the like.

The general objects of the invention are ease and rapidity of construction, simplicity 20 and economy in wall construction.

More particular objects are to dispense entirely with outside bracing, with ties through the wall, and with ties above the wall.

25 Further objects are to obtain quick and accurate setting of the forms and to obviate the formation of lips or other unevennesses on the wall.

Other objects and advantages of my invention will appear from the following description.

In carrying out my invention I provide a form having a mold-face extending above the finished part of the wall and having a 35 supporting portion detachably secured to such finished part of the wall, the form being adapted to be raised by successive steps as the building of the wall progresses.

My invention includes a guide forming 40 a foundation to facilitate the setting of the form and having a mold-face forming a continuation of the mold-face of the form and thereby preventing the formation of a lip or offset on the face of the wall.

45 My invention also includes a mold-bolt adapted to support an anchor which is to be permanently embedded in the wall, the mold-bolt, before the concrete sets hard around it, being replaced by an anchor-bolt of smaller diameter.

My invention also includes the employment of uprights as cantalivers to adjust and hold the mold-face.

My invention further includes several details of construction and combinations of 55 parts, as will hereinafter appear.

I shall now describe my invention with reference to the accompanying drawings and shall thereafter point out my invention in claims.

Figure 1 is an elevation of a portion of the complete mold in place on a wall in course of construction, shown as partly broken away. Fig. 2 is an end elevation of what is shown in Fig. 1 as viewed from the left, the 60 wall being in section. Fig. 3 is a detail horizontal section on a plane indicated by the line 3-3 of Fig. 1, looking downward. Fig. 4 is a similar view on a plane indicated by the line 4-4 of Fig. 1. Fig. 5 is a 65 view similar to Fig. 2, but with one more layer added to the wall and showing the form in course of removal. Fig. 6 is an enlarged side view of one of the mold-bolts, with a portion broken out. Fig. 7 is a similar view of one of the anchor-bolts. Fig. 8 is a similar view of one of the extension 70 bolts. Fig. 9 is an enlarged central longitudinal section of a sleeve-nut for connecting the extension-bolt to the anchor-bolt. Fig. 10 is an enlarged end view of an anchor-nut. Fig. 11 is an axial section of the 75 anchor-nut shown in Fig. 10, viewed from the right.

In the embodiment of my invention illustrated in the drawings a form is shown as comprising lagging 12, forming a mold face, uprights 13 and waling 14, all secured firmly together, for example by nailing and by lag screws 15. The form described is shown as 80 supported by a finished portion 16 of the wall in course of construction. The uprights 13, as shown in Figs. 1 and 2, extend some distance both above and below the upper edge of the finished portion 16 of the 85 wall, the lower portion of the form supporting the upper portion, which carries the lagging 12.

An upper guide 17, shown as composed of two boards and short vertical cleats, is 100

supported at the top of the form by the lagging 12 and uprights 13 and has a mold-face continuous with the mold-face of the form, so that the guide 17 when in place, as shown in Figs. 1 and 2, forms part of the mold. The upper guide 17 carries mold-bolts 18 having reduced screw-threaded end portions, as most clearly seen in Fig. 6. These mold-bolts 18 support on their screw-threaded ends anchor-nuts 19 which are adapted, together with the projecting portions of the mold-bolts, to be embedded in the fresh concrete forming the next upper layer 20 of the wall, as shown in Fig. 5. The mold-bolts 18 are removed before the concrete has finally set, leaving the anchor-nuts 19 permanently embedded in the wall and leaving holes leading to the anchor-nuts which, when the concrete has finally set, will be very slightly smaller than the larger unthreaded portions of the mold-bolts, but of larger diameter than the threaded bolt-receiving holes in the anchor-nuts 19. Into these holes in the concrete are inserted anchor-bolts 21 of smaller diameter than the mold-bolts 18 and provided with screw-threaded ends corresponding to the screw-threaded anchor-nuts 19 into which they are screwed, as shown in Figs. 2 and 5.

The anchor-bolts 21 are shown as supporting a lower guide 22 in all respects similar to the upper guide 17. In fact the lower guide 22 was formerly an upper guide and carried anchor-supporting mold-bolts which have now been removed and replaced by the anchor-bolts 21. The lower guide 22 constitutes both a foundation rest and a guide for the form comprising the lagging 12, uprights 13 and waling 14. By reason of the fact that the lower guide 22 has not been removed since it was an upper guide, it maintains a close contact relation to the wall and its top edge projects slightly above the finished portion of the wall, so that when the form is placed in position thereon, as shown in Figs. 1 and 2, the mold-faces of the form and of the lower guide 22 register and form a continuous mold-face, thereby obviating any possibility of uneven joining of adjacent upper and lower layers of the wall, whereas heretofore commonly a slight overhang or lip was formed at the junction of the two layers, due to the fact that it is impossible for a newly placed mold face to fit as closely and perfectly to the finished portion of the wall as did the mold-face against which it was poured. The guides of the present invention entirely overcome this difficulty and also greatly facilitate the setting of the form.

The anchor-bolts 21 are threaded at both ends and are provided at their outer ends with reduced smooth portions, as appears in Fig. 7, in order that they may be passed

through the lower guide 22 and screwed into the anchor-nuts 19 without danger of spoiling the outer threads. Screwed on the outer ends of the anchor-bolts 21 are sleeve nuts 23 which serve the double function of retaining the lower guide 22 in place on the anchor-bolts 21 and of receiving the inner screw-threaded ends of mold-supporting or extension bolts 24. These extension-bolts 24 are screw-threaded at both ends, as most clearly shown in Fig. 8, and pass through the upper waling piece 14 and receive at their outer ends large washers 25 and ordinary nuts 26. The form is thus supported on the lower guide 22 and is secured to the finished portion 16 of the wall near its top by the anchor-nuts 19, anchor bolts 21, sleeve-nuts 23, extension-bolts 24, and outer nuts 26 (Figs. 2 and 4).

It is to be noted that not only do the uprights 13 extend upward from the upper waling piece 14 above the top of the finished portion of the wall and support the lagging 12 and upper guide 17, but they extend substantially an equal distance downward from the upper waling piece below the top of the wall and act as cantilevers to hold the form in upright position. The lower edge of the mold-face formed by the lagging 12 is guided by the lower guide 22, as above explained, and the mold-face, formed by the lagging 12 and the upper guide 17, may be angularly adjusted to bring it into alignment with or in other desired relation to the face of the finished portion 16 of the wall, by adjustment of the lower ends of the cantilever uprights 13 to and from the wall. The means shown for effecting this adjustment comprise combined adjusting and steadyng bolts 27 and wedges 28.

The adjusting bolts 27 are in all respects similar to the mold-supporting extension bolts 24 except that they are longer. The adjusting bolts 27 pass through the waling piece 14 and enter the holes in the concrete which were last occupied by the anchor-bolts 21, and are screwed into the embedded anchor-nuts 19. The outer ends of the adjusting bolts 27 are provided with washers and ordinary nuts 29. The wedges 28 are driven between the lower portions of the cantilever uprights 13 and the wall 16. By loosening the wedges 28 and tightening the nuts 29 the upper portions of the mold-form will be thrust outward, while by a reverse operation such upper portions will be moved inward.

It will be noted that the adjusting bolts 27 coöperate with the anchor in the layer or section below the last one hardened, and hence the mold may be moved up sooner than would be the case if the mold were supported only by the last hardened layer.

In operation, when an upper freshly

5 poured wall section, such as 20 (Fig. 5); has sufficiently hardened to support the mold-form, the form is detached, as shown in Fig. 5, and is raised to a position above the upper guide 17, which then becomes a lower guide, the mold-bolts 18 first having been removed and been replaced by anchor-bolts 21. The lower guide 22 is then removed from the position shown and secured at the top of 10 the form and becomes in its turn an upper guide, and the mold-bolts 18, with the anchor-nuts 19 thereon, are inserted in it. The adjusting bolts 27 are inserted into the holes in the wall just vacated by the anchor-bolts 15 21, and the form is adjusted and fully secured in place on the upper wall section or layer 20 in the same manner that it was previously secured on the lower portion 16 of the wall. It is to be noted that the guides 20 17 and 22 are alternately supported by the form and act as guiding foundation supports therefor, and that the anchor-bolts 21 successively replace the mold-bolts 18, and the adjusting bolts 27 in like manner replace 25 the anchor-bolts 21. If desirable, the holes left in the wall after the removal of the adjusting bolts 27 may be readily filled with concrete.

It is obvious that various modifications 30 may be made of the construction shown and above particularly described within the principle and scope of my invention.

I claim:

1. In combination with a mold for concrete walls including a mold-face and a waling spaced from the mold-face, an anchor adapted to be embedded in the fresh concrete, a mold-bolt extending from the mold and supporting the anchor and adapted to 25 be disengaged from the anchor and removed before the concrete has completely hardened, an anchor-bolt adapted to replace the mold-bolt and engage the anchor, the anchor-bolt when in engagement with the anchor extending 40 with its outer end between the mold-face and the waling, a mold-supporting bolt extending through the waling, and a sleeve nut disposed between the mold-face and the waling and connecting the anchor bolt and 45 the mold-supporting bolt.

2. In combination with a mold for concrete walls including a mold-face and a waling spaced from the mold-face, an anchor adapted to be embedded in the fresh concrete, a mold-bolt having an end of reduced 55 diameter, which mold-bolt extends from the mold and supports the anchor on its reduced end and is adapted to be disengaged from the anchor and removed before the concrete 60 has completely hardened, an anchor-bolt of the diameter of the reduced end of the mold-bolt and adapted to replace the same and engage the anchor, the anchor-bolt when in engagement with the anchor extending with

its outer end between the mold-face and the 65 waling, a mold-supporting bolt extending through the waling, and a sleeve nut disposed between the mold-face and the waling and connecting the anchor-bolt and the mold-supporting bolt. 70

3. A three-part mold for concrete wall construction comprising a form having an upright, a mold-face carried thereby, and two similar guides adapted to serve alternately as lower and upper guides as the 75 form is raised by successive steps; each guide being adapted when serving as an upper guide to be supported on the mold face and to form a continuation thereof, and when serving as a lower guide to be supported by 80 the wall and to support the rest of the form, the mold-face being free from direct connection with the wall.

4. A three-part mold for concrete wall construction comprising a form having a 85 plurality of uprights, a mold-face carried thereby, and two similar guides adapted to serve alternately as lower and upper guides as the form is raised by successive steps, and to form continuations of the mold-face; and 90 permanent anchors detachably carried by the upper guide and arranged to be embedded in the wall, the lower guide being adapted to be supported by the permanent anchors and to support the rest of the mold, 95 the mold-face being free from direct connection with the wall.

5. A mold for concrete wall construction comprising a form provided with a mold-face and having cantaliver uprights supporting the mold-face and extending below the mold-face for a distance exceeding the width of the mold-face, walings secured to the uprights, an upper and a lower guide, anchors 100 detachably carried by the upper guide and adapted to be permanently embedded in the wall, mold-bolts for connecting the anchors to the top guide, anchor-bolts of smaller diameter than the mold-bolts at the median portions of the cantaliver uprights and passing through a waling and the lower guide, and adapted to engage the anchors last embedded in the wall, and adjusting-bolts at the lower ends of the uprights adapted to engage the anchors in a 105 series below those engaged by the anchor bolts. 110

6. A three-part mold for concrete wall construction comprising a form having a plurality of uprights, a mold-face carried 120 thereby, and two similar guides adapted to serve alternately as lower and upper guides as the form is raised by successive steps, and to form continuations of the mold-face; anchors carried by the upper guide and adapted to be permanently embedded in the fresh concrete, removable mold-bolts detachably connecting the anchors to the upper guides, 125

and anchor-bolts of smaller diameter than the mold-bolts arranged to detachably engage the anchors embedded in the wall and support the lower guide; the lower guide being engaged to support the rest of the mold and the mold-face being free from direct connection with the wall, and the uprights extending a substantial distance be-

low the lower guide and adapted to serve as cantalivers.

In testimony whereof I have affixed my signature in presence of two witnesses.

ALEXANDER P. CRARY.
